UNITED STATES PATENT OFFICE

RICHARD LANGE, OF LEONIA, NEW JERSEY

METHOD OF AFFIXING STAMPING MATERIAL TO BOOK COVERS AND THE LIKE

Application filed May 24, 1930. Serial No. 455,299.

This invention relates to an improved method of applying and affixing a stamping medium such as roll leaf, bronze composition, and the like, to book covers or cases and similar articles and has for its object the production of a more expeditious mode of treatment for applying and affixing stamping medium to book covers and other articles to be thus embellished, stamped or printed.

A further object includes a mode of treatment for stamping and embellishing book covers, and the like, whereby the stamping material is applied and affixed by a series of continuous, successive steps in such a manner as to give the complete product a clean cut outline and superior finish.

It is further my purpose to apply the roll leaf or equivalent stamping and embellishing material to the book covers or other articles to be stamped, embellished or printed in stages, that is to say, the stamping material is first applied to the book cover with just sufficient pressure and under suitable conditions of temperature to fully attach the medium onto the surface of the book cover or other article. This step may be performed by use of a suitable die, plate or printing characters operated by suitable mechanism, or by hand, and with sufficient pressure to thereby attach the stamping medium to the surface of the book cover without depressing the material into the surface at all or only slightly. I then separate the die or other stamping unit from the applied stamping material and brush or otherwise clean the stamping unit. The cleaning may be done in any desired manner, as by moving said stamping unit away from the stamping material and over a brush, or by brushing the same so as to obtain a clean surface for the next step of impressing the stamping. This step is applied under such conditions as will impress or embed and affix the stamping material into the surface of the book cover and integrally unite the same with the surface and at the same time burnishing the stamping material thus united. For convenience this step may be called the affixing step and is substantially as follows:

The book cover or equivalent and the clean stamping unit are advanced laterally

and brought together in relatively the same position as was had when the stamping medium was attached to the surface of the book cover. The book cover is preferably moved from the stamp applying position to the stamp affixing position and the stamping unit is similarly moved to the new position so that the stamping unit registers perfectly with the original stamping impression. Pressure is now supplied to the book cover and stamping unit; that is, these elements are brought together under suitable conditions of pressure and temperature to impress the stamping material into the surface of the book cover or other article and at the same time burnish the stamping. The contact between the stamping unit and embellished surface is then broken by withdrawing either the book cover or the stamping unit, or both.

The next step comprises cleaning the impressed cover so as to remove any superfluous stamping medium. This may be done by brushing (under a vacuum if desired) the stamped surface so as to remove all loose particles of stamping material from the book cover. The next step embraces the application of a protective coating material such as a solution of collodion which may be applied in a suitable manner such as spraying, brushing, or the like. It is my purpose to cover the embellished portion as well as the book cover itself to thus fully protect the cover and the embellished portion. After spraying the coating is dried and the book cover is ready for use. The article thus produced has a clean, clear cut outline, a superior finish and will withstand wear and tear for a long period of time.

The several steps may be summarized as follows:

1. Supplying and applying the book covers.
2. Applying or laying on the stamping medium such as metallic leaf.
3. Cleaning or brushing the leaf applying means.
4. Impressing, that is, affixing and burnishing the applied stamping medium.
5. Removing free stamping medium.

6. Applying a protective coating.
7. Drying the protective coating.

These steps may be carried out by any desired instrumentalities and in the accompanying drawing I have shown a somewhat diagrammatic representation to illustrate the different steps as applied to book covers. It is, of course, understood that the expression "book covers" is used in a generic sense and that the process or mode of treatment is applicable to other articles or surfaces that may be thus treated.

Referring now to the drawing:

Figure 1 shows means for supplying book covers and represents the step of laying on or applying the stamping medium;

Fig. 2 represents the die cleaning step and the step of impressing and burnishing the applied stamping medium;

Fig. 3 shows the successive steps of removing free stamping medium from the cover, also of applying a protective coating medium to the book cover and of drying the same.

If book covers are to be treated then these may be supplied by any suitable means as, for example, from a stack 10 by a suction device 11 which picks up the book cover and deposits it on a conveyor 12. The book cover 13 is then placed in position on the printing bed 14 immediately beneath the die or printing unit 15 which is slidably held in the heated head 16. A strip of stamping medium 17 is held between the book cover and the die so that the same will be brought into contact with the book cover when the impress is made. In the first position the impress is but lightly made so as to lay on the stamping material or, at most, impressing it but very slightly. These two stages are shown in Fig. 1 where 13^a represents the book cover with the stamping medium 17^a placed thereon lightly, while 13^b represents the book cover with the stamping medium 17^b slightly impressed. The next step in the successive process requires the removing of loose stamping medium from the printing unit. This is accomplished by any suitable means such as a brush 18 over which the printing unit is caused to slide into the affixing position in which position the step of affixing or impressing and burnishing is accomplished.

The impressing and burnishing step is accomplished by applying the printing unit onto the stamping medium in the exact relative position that it had when the first impress was made. That is to say, the printing unit and the cover to which the stamping is now attached, are both moved to the impressing position and then brought together in substantially their exact relative position and pressure is applied at suitable temperature to impress the stamping material into the surface of the cover as is shown at 17^c and 13^c. The stamping is burnished at

the same time and a clean, sharp edged impress is obtained. After the stamping medium has been applied, affixed and burnished the book cover as well as the embellished or stamped portion is cleaned in any suitable manner. This may be accomplished by placing the book covers on a suitable conveyor 19 for passing the same through the cleaning step (5) and then to the next step (6) which is that of coating the stamping and book cover with a protective transparent coating. After the coating step the cover is passed on through the drying step (7). The drying may be accomplished by any suitable manner as by a rack 20 which picks up the books and delivers them to the bottom of a stack 21. It will be seen from the above that the several steps which constitute the process are carried out in a continuous and successive manner so as to provide book covers and other like articles with a stamping medium which is properly fixed and burnished as well as protected and which has clean, clear cut edges and superior finish. It is obvious that other instrumentalities may be employed for carrying out the several steps above described.

I claim:

1. The method of applying and affixing a stamping medium to a book cover and like article, which comprises affixing a stamping medium to the surface of a book cover, then moving said cover and stamping and again impressing the affixed stamping medium into the surface of the book cover and burnishing the same, then cleaning said cover, then applying a protective coating material and drying said coating material.

2. That method of applying and affixing roll leaf to book covers and the like which comprises attaching said roll leaf to the surface of a book cover with sufficient pressure to cause the roll leaf to adhere to the cover, then shifting the book cover and stamping and impressing said roll leaf into the surface of the book cover and burnishing the same, then removing the surplus of roll leaf from the cover, then applying a coating material to the impressed surface and book cover, and finally drying the coating.

3. That method of applying and affixing roll leaf to book covers and the like, which comprises bringing the roll leaf and the book cover into intimate contact to cause the roll leaf to adhere to the book cover, then cleaning said leaf applying means and again bringing the same onto the book cover in substantially the same relative position as was had in the leaf affixing step, then applying pressure to impress the roll leaf into the surface of the book cover, then removing from said impressed surface any free roll leaf, then spraying the book cover and impressed surface with a solution of collodion and drying the same.

4. That method of applying and affixing

a stamping medium to book covers and like articles, which comprises supplying book covers in arranged order, then applying a stamping medium to the surface of the successive book covers, then moving the book covers laterally to new position and again applying pressure to the applied stamping medium so as to impress the same into the surface and burnish at the same time, then removing free stamping medium, then applying a protective coating and drying the same.

5. The step of applying and affixing stamping medium to book covers and like articles, which comprises impressing stamping medium lightly onto the surface of a book cover or other article, then cleaning the impressing means and again applying said means to the stamping medium from a different position in the same plane with increased pressure to impress the stamping medium into the surface and burnish the same.

6. That method of applying and affixing stamping material to an article in stages which comprises applying the stamping lightly in the first stage, then moving the stamping laterally and removing loose stamping particles and impressing the applied stamping into the surface of the article.

7. That method of applying and affixing stamping material to an article which comprises applying said stamping material with sufficient pressure to attach the same to the article, then moving said article and cleaning the stamping means and again applying the same with increased pressure to said article for the purpose of permanently affixing and impressing said stamping material into the surface of the article, then cleaning the article and coating the same.

8. That method of applying and affixing stamping material in stages to an article to be stamped or ornamented which comprises attaching the stamping material to the article, then moving the stamp applying means and article to new positions and again applying pressure so as to affix the stamping material and then brushing.

9. That method of applying and affixing stamping material to an article which comprises supplying and registering said article, then laying on the stamping material on the article to attach the same thereto, then moving the article and stamp affixing means laterally and brushing the stamp applying means and again impressing said stamping material, burnishing the same.

In testimony whereof I have hereunto set my hand on this 16th day of May, A. D. 1930.

60 RICHARD LANGE.
